METHOD OF AND MEANS FOR DESALTING
PETROLEUM WELL FLUIDS

Jay F. Walker, Tulsa, Okla., assignor of forty per cent to Guy O. Marchant and six per cent to C. G. Wells, both of Tulsa, Okla.

Application April 28, 1941, Serial No. 390,727

7 Claims. (Cl. 252—343)

This invention relates to new and useful improvements in the treatment of petroleum well fluids.

One object of the invention is to provide an improved method for treating a well fluid stream as it is produced from a well, whereby the oil, gas and water mixtures or emulsions are separated and also whereby salts or other corrosive or harmful ingredients are removed from said stream in a continuous, uninterrupted operation.

Another object of the invention is to provide an improved method of treating and de-salting an emulsified well stream from a crude-producing well, wherein the breaking of the emulsions and the de-salting of the stream may be accomplished in a single vessel or tank and in one operation, or, if desired, these steps may be performed in two stages; however, in either instance, the method is carried out continuously and immediately upon removal of the stream from the well.

An important object of the invention is to provide an improved method of de-salting well streams which may be carried out at relatively low temperatures and at atmospheric pressures, or even under vacuum if desired, whereby the use of high pressure vessels is obviated.

A particular object of the invention is to provide an improved method, of the character described, wherein fresh water is constantly introduced into the flow stream to absorb the salt in said stream and thereby de-salt said stream; the method also contemplates heating of the flow stream to break up emulsions and the addition or introduction of the fresh water may take place either prior or subsequent to the heating step, whereby the method is flexible and capable of variation to meet various conditions.

Still another object of the invention is to provide an improved method wherein the well influent which may be an emulsion of oil and water, or water, emulsion and free oil and some gas, is treated to extract or precipitate the major portion of the water, such extraction being accomplished either by pre-heating or by the use of well-known chemicals, or by both; the well stream is then heated and treated to break the emulsion, and the stream is also de-salted, the de-salting step taking place either simultaneously with the treating step which breaks the emulsion, or immediately subsequent thereto.

A further object of the invention is to provide an improved method wherein the well fluid containing salt water and extraneous matter is introduced into a body of salt water, together with

a quantity of fresh water, whereby the well fluid and the fresh water co-mingle and admix with each other and are caused to pass through said body of salt water. Since the fresh water is much lighter than the salt water, its natural tendency is to rise with the oil and thereby become thoroughly admixed with such oils while passing through the salt water zone, which results in a washing or absorbing method causing the fresh water to become saturated with the salt from the well fluid stream. The oil will thus be denuded of its water content whereby the salt will be extracted from the well stream and clean oil will float upon the water and stratify above the same, after which said oil may be readily drawn off free from both salt and water.

A still further object of the invention is to provide a method, and means for carrying out the same, wherein the oil and fresh water stream, during their settling period, are allowed to rise concurrently, free of counter-current flow of descending salt water, and the water precipitated and removed from the path of the ascending oil and water stream as rapidly as it is precipitated.

The construction designed to carry out the invention will be hereinafter described, together with other features of the invention.

The invention will be more readily understood from a reading of the following specification and by reference to the accompanying drawings, as an example of the invention is shown, and wherein:

Figure 1 is a view partly in elevation and partly in section of an apparatus constructed in accordance with the invention, for treating and de-salting the well fluids.

Figure 2 is a horizontal, cross-sectional view, taken on the line 2—2 of Figure 1.

Figure 3 is a horizontal, cross-sectional view, taken on the line 3—3 of Figure 1.

Figure 4 is a view, similar to Figure 1, illustrating a slight modification, wherein the well fluids are treated to break emulsions.

Figure 5 is a transverse, vertical, sectional view of a de-salting tank which has connection with the vessel illustrated in Figure 4.

Figure 6 is a transverse, vertical, sectional view, taken on the line 6—6 of Figure 5.

Figure 7 is a horizontal, cross-sectional view, taken on the line 7—7 of Figure 4.

Figure 8 is a horizontal, cross-sectional view, taken on the line 8—8 of Figure 4, and

Figure 9 is a horizontal, cross-sectional view, taken on the line 9—9 of Figure 4.

This application is filed as a continuation-in-part of my co-pending application, Serial No. 164,181, filed September 16, 1937.

In the drawings, the numeral 20 designates an upright cylindrical tank of the usual construction such as is used in the building of separators. The tank is provided with a suitable base 21 and a false bottom 22. A dished head or partition 23 is secured within the tank near the upper end thereof, while the extreme upper end of said tank is closed by a crowned top 24. The members 23 and 24 seal off the upper portion of the tank and form a preliminary or primary separating chamber 25. The chamber 25 could be a separate container or tank.

A transverse partition 26 extends across the separating chamber 25 (Figure 1), being disposed nearer the upper end thereof, whereby a gas separating chamber C is formed in the upper portion of the chamber 25. This partition is inclined and is provided with a central outlet 27 from which a tubular sleeve 28 extends. A conical spreader 29 is suspended axially from the sleeve 28 and is disposed below the outlet opening 27 and within the interior of the chamber 25. The spreader serves to spread the liquids escaping through the outlet opening 27 into the chamber 25.

An inlet pipe 30 extends through the wall of the tank 20 and discharges into a diverter box 31, within the gas chamber C, whereby the well stream or influent is caused to take a circumferential and helical course around the inner wall of the tank. The influent is scrubbed on the wall of the tank, whereby the liquids flow downwardly in the chamber C, while the gaseous fluids which are separated, rise so as to enter an axial gas separating shell 32 through inlet openings 33. The gaseous fluids or vapors are caused to whirl within the shell, whereby the gas is liberated and the liquids are dropped out. From the gas shell 32, the gas is carried off through a suitable outlet pipe 34 which usually has a control valve (not shown) connected therein. A liquid drain pipe 35 depends from the bottom of the shell and extends through the partition 26, whereby the separated liquids are discharged into chamber 25 flowing through said outlet.

The liquids which have been primarily separated from the gas but which may contain some gas in solution, flow through the opening 27 and fall downwardly onto the conical spreader 29, which directs the liquids into the chamber 25. It is pointed out that the upper chamber C could be eliminated, in which instance, the influent from the pipe 30 will be conducted directly into the chamber 25.

Within the separating chamber 25 is an upright overflow pipe 36, said pipe being mounted at one side of the chamber. The lower end of the pipe terminates adjacent the head 23, while the upper portion thereof terminates near the partition 26. This pipe is divided into a water leg and a gas leg by a lateral 37 leading from the intersection of the two legs through the side of the tank. A down pipe 38 leads from the lateral to a water siphon box 39 and includes a regulating valve 40. The box has an upright, overflow nipple 41 therein and this nipple is connected to a water discharge pipe 42. Manifestly, water from the chamber 25 may flow upwardly through the water leg of the pipe 36, then through the lateral 37 and downwardly to the water discharge pipe 42. The elevation or position of the lateral 37 will control the water level within the chamber 25.

A conductor or pipe 43 extends from the oppo-

site side of the chamber 25 and establishes an oil level (Figure 1) above the spreader 29. The lateral 37 establishes a water level within the pipe 36, which owing to the hydrostatic head caused by the floating oil is higher than the water level in the chamber 25. A transverse filter 44 extends across the lower portion of the chamber 25 below the water level. The filter may be formed of excelsior or other suitable material confined between screens or perforated partitions 45. A vent pipe 46, hereinafter referred to, extends through the bottom 23, up through the filter 44, partition 26, and terminates in a hood 47 at the upper portion of the chamber C.

15 The well stream or influent liquids discharging through the sleeve 28 depending from the lower end of the chamber C and falling upon the spreader 29 will spread therefrom in a more or less circumferential sheet which will have a tendency to liberate gas and to spread out the water-oil globules. The oil will tend to float and rise while the water will settle or precipitate. Those water-oil globules or droplets which reach the filter 44 will be broken up in attempting to pass therethrough, whereby the water will pass through the filter and the oil will float and rise to the oil zone above the water level. As the water settles in the main chamber 25, it will rise in the pipe 36 and will discharge through the lateral 37.

20 30 The water and oil levels in the chamber 25 will define water, oil and gas spaces or zones therein. It is pointed out that the major portion of the gas is separated from the influent in the chamber C. The remaining liquids, with some gas in 35 solution, then pass into the primary separating chamber 25 where a major portion of the water is separated. However, all the water does not settle out in the chamber 25, and, thus, the liquids entering or overflowing into the pipe 43 comprise 40 oil with, perhaps, some gas in solution, and some water admixed therewith, which is an emulsion mixture requiring further treatment. While gas is separated in the chamber C, the gas might be previously extracted, or if no gas separation was 45 necessary, the gas separating step could be omitted.

The influent may be pre-heated, if desired, and any suitable device may be used for the purpose. A pre-heater 48, similar to that shown and described in my Letters Patent No. 2,181,685, may be employed. In this device, the oil, gas and water mixture enters through an inlet pipe 49 at the bottom and flows upwardly through a plurality of tubes 50 to the top of the pre-heater and the inlet pipe 30 is connected to the top of said pre-heater. A hot oil discharge or outlet pipe 51 extends from the tank 20 at the oil level therein and connects to the upper portion of the pre-heater, whereby the hot oil flows down around the tube and escapes through an outlet 52. The counter-flowing influent and oil undergo 55 a heat exchange, whereby the influent is pre-heated and the oil is cooled. A gas escape pipe 50a connects the oil space of the pre-heater with the tank above the oil outlet pipe 51.

60 The pipe 43 which leads from the chamber 25 extends downwardly along the outer surface of the tank. At its lower end, the pipe 43 is connected to one end of a horizontal nozzle 53 which 65 extends diametrically across the tank, as is thus shown in Figure 1. A suitable manually controlled valve 54 may be connected in the pipe 43 on the outside of the tank, whereby the flow of liquids or fluids through said pipe may be readily controlled, but the valve is not essential to the

invention. The nozzle 53 is usually placed a suitable distance above the bottom 22 to provide a water settling and collecting space therebelow, in which extraneous matter may also deposit. The nozzle is preferably provided with longitudinal rows of perforations 55 on its upper side so as to discharge the liquid mixture upwardly in numerous small streams. The tank contains a body of water, usually salt water, up to a certain level which is maintained by a siphon pipe 56. This pipe has one end connected to the siphon box 39 located outside of the tank, while its lower end extends downwardly to the bottom of the tank. In this manner, water is drawn upwardly through the pipe, discharged into the siphon box, and then escapes through the water outlet pipe 42. Obviously, due to the hydrostatic head within the tank, the water level will be maintained at a point below the lateral leg or horizontal portion of the water pipe 56. A gas vent pipe 57 extends from the upper portion of the siphon 39 and is provided with a vertical portion which terminates adjacent the underside of the partition or head 23. With this arrangement, water is discharged from the upper chamber 25 and also from the lower chamber by means of a single water discharge pipe 42. It will be seen that gas is vented not only through the pipes 46 and 57, but also through the upper area of the lateral 37 and gas leg of the pipe 36. By making the nipple 41 in the siphon box 39 adjustable, predetermined liquid levels in the lower chamber of the tank may be maintained.

From the foregoing, it will be seen that the liquids and fluids conducted downwardly through the pipe 43 from the upper chamber 25 are discharged through the nozzle 53 and upwardly within the lower portion of the tank in numerous small streams. A heating unit 58 is disposed within the tank above the nozzle 53 and this unit is shown as a U-shaped tubular or return bend fire box 29 which is mounted in a manhole cover 60, the latter being attached to a rectangular frame 61 which is attached to the upright wall of the tank 20. Removal of the cover will permit the unit to be taken out of the tank for cleaning or replacement. The lower leg of the box rests upon a supporting channel bar 62 which extends across the tank. A suitable burner (not shown) may be introduced into the lower leg of the box, while the upper leg of said box is closed at its outer end and provided with a collar 64 to which a suitable stack may be attached.

Inclined baffles 65 are located above the nozzle 53 and serve to direct the small upwardly flowing streams against the bottom of the lower leg of the fire box and to flow upwardly on each side thereof, whereby they are heated. Similar inclined baffles 65a overhang the fire box and maintain the upwardly flowing streams in heating contact therewith.

A vertical housing 66 is mounted within the tank above the fire box 58 and this housing includes vertical walls 67 which extend on each side of the fire box and nozzle, as is clearly shown in Figure 1. The vertical edges of the walls 67 are secured to the inner wall of the tank, whereby vertical passages, or ducts 68, open at their upper and lower ends, are formed with the wall of the tank. Above the fire box and within the housing 66, staggered, upwardly inclined cross-baffles 69 are provided and these baffles may have their free ends serrated to divide upwardly flowing liquids into numerous small streams. One end of each baffle is secured to the wall of

the tank, while the other end terminates short of the tank wall, whereby the staggered baffles provide for a circuitous or elongate path through which the upwardly moving liquids must travel.

5 Water drain openings 70 are provided in each side wall 67 of the housing near the lower ends of the baffles 69. Obviously, liquids which drain downwardly along the baffles 69 may flow outwardly through the drain openings 70 and into the vertical flow passages 68 on each side of the housing.

The space between the inclined baffles 69 is filled with a suitable filtering material 71, such as excelsior, hay or other material suitable for the purpose. Thus, liquids flowing upwardly through the housing formed by the side walls 67 and the inclined baffles 69 is forced to pass through the excelsior, or other filtering material, before reaching the space within the tank above the housing.

15 20 As explained, the lower portion of the tank is filled with a body of water, which is preferably salt water, and this body is heated by means of the fire box 58. The liquids flowing through the pipe 43 which leads from the upper chamber 25 are introduced into this body of heated salt water through the nozzle 53 and said liquids rise upwardly through the body of salt water. For introducing fresh water into the tank 20, a water inlet nozzle 72 is disposed within the lower portion of the tank above the nozzle 53. The water inlet nozzle 72 is provided with a plurality of perforation 73 in its upper surface, whereby the water is ejected therefrom in numerous small streams. As is clearly shown in Figure 1, the water nozzle 72 is supported on a suitable angle bracket 74 and has its outer end connected by means of a coupling 75 with a fresh water inlet line 76. The fresh water is introduced into the tank so as to absorb the salts which may be present in the well liquids introduced through the nozzle 53.

30 35 40 Briefly, in operation, the influent is brought through the inlet pipe 49 from the well. This influent may be an emulsified stream from a crude producing well and may include oil mixed with salt in solution, or salt in any form, and extraneous matter, such as dirt or silt. The term "well fluids" and "influent" as used herein covers any fluid produced by a well, either liquid or gaseous, or both and including, oil, water, gas, salt and extraneous matter or any of them, and in such association as they may occur or be admixed.

45 50 55 The influent from the pipe 49 is taken through the pre-heater 48, wherein it is heated in order to precipitate free water. From the pre-heater, the influent is discharged into the diverter box 31 within the chamber C and said influent is thereby whirled around the tank on the inner surface thereof. This circumferential action scrubs out a considerable amount, possibly the 60 major portion of the gas; some gas, however, will remain in solution. The liberated gas and gaseous fluids rise and enter the shell 32, wherein they are whirled and the liquids are scrubbed out. These liquids drain through the pipe 35 65 into the separating chamber 25. The remaining influent liquids will pass through the outlet opening 27, and will fall upon the spreader 29, and then into the chamber 25.

70 75 As before described, the water, oil and gas stratify in the chamber 25, the filter 44 breaking up the oil-water globules and water droplets. The water extracted in the chamber 25 flows upwardly in the pipe 36 from which it escapes through the lateral 37 and siphon box 39 to the water outlet pipe 42. The oil and water mixture

flows out through the pipe 43 and downwardly in said pipe until it is discharged from the nozzle 53 through the perforations 55. This mixture, which may contain salt, or other extraneous matter is baffled upwardly through the body of heated salt water within the tank 20. As the heated mixture flows upwardly, the baffles will wash out the entrained water which is admixed with the oil and the water which is thus washed out will tend to run down the upper sides of the baffles and drain through the openings 70 into the passages 68. By the time the mixture reaches the top of the housing 66, the entrained water will be substantially washed out of the oil-and-water mixture and the clean oil will rise and float upon the body of water up to the oil level. The water which drains into the passages 68 flows downwardly and cools, finally admixing with the water in the bottom of the tank, whereby said water is re-circulated. The oil is, of course, taken off through the oil discharge line 51, through the pre-heater 48 and finally out through the oil outlet line 52.

From the above, it will be seen that the emulsion is broken up and the oil and water efficiently separated. At the same time that liquid is discharged from the nozzle 53, fresh water is supplied by the nozzle 72. This fresh water is discharged immediately below the heating unit 58 and flows upwardly in small streams with the influent, whereby all the fluids and liquids thereby become thoroughly admixed. The influent and the fresh water are obviously in close proximity to the heating unit before passing upwardly through the baffles 69 within the housing.

Since the fresh water is so much lighter than the salt water, its natural tendency is to rise with the oil and thereby become admixed with it while flowing upwardly through the heated body of salt water. During this flow there is more or less of a washing or contacting of the fluid whereby the fresh water is agglomerated with the salt component of the influent. Further, extraneous matter, together with such salts as solidify will tend to settle in the housing section toward the bottom and escape to the bottom of the tank. The commingled fluids will pass upwardly between the baffles 69 and through the filters 71 disposed between said baffles.

The admixed fluids and liquids will contact the underside of the lowermost baffle plate 69 and this step will act to strain water and extraneous matter from the fluids and liquids. The admixture will travel laterally along the inclined bottom of the baffle plate toward its upper end whereby water-oil emulsion globules will be broken up. The admixture will pass around the end of the baffle plate and then flow along the underside of the next baffle where the operation will be repeated. Obviously, continued upward flow will cause the mixture to take the circuitous path back and forth across the tank and through the filters 71. This prolonged travel, together with the filtering will thoroughly carry out the de-hydration and de-salting of the oil. Water and extraneous matter which is extracted during the upward travel will flow down the upper side of the baffles and will escape through the openings 70 in the side walls of the housing and will enter the vertical passages 68. The heavier components and extraneous matter will settle to the bottom 22. A valve outlet 21' is provided in the bottom 22 for periodically cleaning out the tank and for draining off salt water manually, if desired.

The fresh water which is introduced provides

for a complete absorption of the salt within the well influent. After the emulsion is broken, the salt crystals in the water which is separated from the oil is absorbed by the fresh water and in this manner substantially all of the salt is removed. It has been found that the salt water body within the tank 20 will become fully saturated and incapable of picking up additional salt after the apparatus has been in use for some time. The addition of the fresh water maintains the body of water within the tank in a condition where it is capable of constantly absorbing additional salt. In effect, the oil is washed through a body of water which is not fully saturated with salt, and this washing is greatly assisted by the particular baffling arrangement as well as by the provision of the filter between said baffles.

In Figures 1 to 3, a single vessel or tank is provided for breaking the emulsions and for simultaneously de-salting the oil. Thus, the emulsion treating and the de-salting are all accomplished simultaneously in the single apparatus. However, the invention is not to be limited to the particular apparatus shown in Figure 1, and in Figures 4 to 9, a slightly modified form of apparatus is shown. In this apparatus, a treating tank, for treating the emulsion is illustrated. This tank is substantially the same in construction as that shown in Figure 1, with the exception that the filters 71 are omitted and also the fresh water inlet nozzle 72 is eliminated. Otherwise, the tank is substantially identical in construction. The well influent is introduced into this tank and is conducted therethrough in the manner above described, whereby the emulsion is broken and the oil is carried off through the discharge line 52. This oil may have salt or other extraneous matter admixed therewith.

After treatment within the tank A, the separated oil is conducted to a second tank B which is clearly shown in Figure 5. The tank B is upright and is of the usual construction, being provided with a false bottom 22 and a crowned top 23'. An inlet nozzle 80, similar in construction to the nozzle 53 is disposed within the lower end of the tank and has connection with the oil discharge line 52 of the tank A, whereby the oil which has been separated in the tank A is sprayed upwardly within the tank B in numerous small streams. A fresh water inlet nozzle 81 is disposed above the nozzle 80 and serves to introduce fresh water into the tank B. A heating unit 58', similar in construction to the fire box 58 is disposed within the tank above the water pipe 81.

An upright housing 82 is provided within the tank B and is formed of an upper section 83 and a lower section 84. As shown in Figure 6, the upper section overhangs the lower section, the latter being of considerable less width than the upper section. The housing sections are formed by upright metal plates 85 and 86. The lower ends of the plate 86 are inclined inwardly below the nozzle 80 to form a hopper bottom and a longitudinal opening 87. The metal plate 86 which forms the sides of the lower housing section confine the heating unit 58' therebetween and extend upwardly beyond the lower ends of the plate 85.

By welding or otherwise securing the vertical edges of the housing plate to the inner wall of the tank, vertical passages or channels 88 (Figure 6) are provided outside of the housing between said plate and the wall of the tank. The walls 85 of the upper section terminate relatively below the upper leg of the fire box 58' and the walls 86 being spaced inwardly of said walls 85, short passages 89

are provided therebetween, as shown in Figure 6. Just above the heating unit and the upper end of the lower housing section is mounted a flanged, perforated baffle plate 90 having its ends suitably attached to the inner wall of the tank within the upper housing section.

Above the plate 90 is an upwardly inclined baffle plate 91 which underlies a second upwardly inclined baffle plate 92. These plates extend from opposite sides of the tank but terminate short of the wall of the tank so as to occupy a staggered relation within the housing. The outer portion of each baffle plate is perforated and the edges may have saw teeth (not shown) if desired. Outlets 93 are provided in the housing walls 85 adjacent the lower ends of the baffles so that liquids which drain down the baffles may escape into the passageways 88 through said outlet.

Above the baffle plate 92 are a pair of divergent filter plates 94, the lowermost plate inclining upwardly with relation to the plate 92 and the upper plate inclining upwardly in the opposite direction below an oppositely inclined baffle plate 95.

The baffle and filter plates which have been described extend across the housing 82 but are confined therein. The filter plates 94 extend from wall to wall of the tank 20 and have perforations 96 at their opposite ends.

The space between the plates 94 is filled with a suitable filtering material 97 such as hay, excelsior or any other material suitable for the purpose. Drain openings 98 above the bottom filter plate 94 are covered with wire mesh to prevent the filtering material passing therethrough. Above the upper filter plate 94 and above the baffle plate 95 the side walls 85 of the housing are provided with the openings 99. The top 83' of the housing is inclined upwardly from the plate 95 and forms a baffle the same as the other plates. It is provided with perforations 100 at its free end opposite the perforations of the plate 95. The free edge or end of the top plate 83' may be provided with downwardly projecting saw teeth, if desired.

The housing extends above mid-height of the tank, whereby a sizable chamber 101 is formed in the upper portion of the tank. In some instances, it may be found desirable to provide a filter in this upper chamber and in such event filtering material 102 may be confined between perforated filtering plates 103 extending diagonally from one side of the chamber at the top of the housing to the upper end of said chamber. It is to be understood that instead of perforations in any of the elements which have been described, screen fabric or any foraminous material may be used. It is to be noted that either of the filters may be omitted and either one or both may be used.

An outlet box 104 may be secured to the tank wall near the top 23' and diametrically opposite the upper end of the filter 102. The upper edge of this box may have saw teeth 105. An outlet collar 106 is secured in the wall of the tank within said box so that oil which drains into the box may be piped therefrom. Theoretically, oil discharged through the outlet 106 will be substantially free from both salt and water.

The operation as the liquids flow upwardly through the tank B is obvious. The fresh water is constantly added and serves to absorb the salt which is present in the oil. Also any water which is entrained in the oil is separated therefrom. A predetermined water level may be maintained in the tank B by an overflow pipe 107 or any other suitable means. The action of the fresh water

in accomplishing the de-salting is the same as has been hereinbefore described. The method which is performed in the tanks A and B shown in Figures 4 and 5 is substantially the same as that performed by the single tank 20 shown in Figure 1, with the exception that the emulsion treating takes place at one stage, while de-salting takes place at another stage. In both methods, the fresh water is added as an absorbent of the salt present in the fluid and is utilized to maintain the body of water in a condition capable of removing the salt from the well fluid. It is pointed out that the method may be carried out under atmospheric or moderately low pressure conditions, or even under vacuum, whereby the necessity of exceedingly high high-pressure vessels is eliminated. Also, the method is carried out at relatively low temperature because it is not necessary that the temperature be maintained sufficiently high to cause evaporation of the water. The fresh water may be added at any stage in the method and it is preferably added after pre-heating of the influent, and free water removal, or after heating takes place in the lower part of the washing chamber.

It will be found advantageous at times to add certain chemicals for the purpose of assisting the breaking up of the emulsion globules, and these chemicals may be added at any point in the method, either ahead of a pre-heater, after a pre-heater, ahead of gas separation, or after gas separation, or as the flow stream enters the washing chamber or after introduction into the washing chamber, or chemicals may be added into the introduced fresh water at any point in the method, and this chemical may be such as to act as best suited for the purpose.

The foregoing description of the invention is explanatory thereof and various changes in the size, shape, and materials, as well as in the details of the illustrated construction may be made, within the scope of the appended claims, without departing from the spirit of the invention.

What I claim and desire to secure by Letters Patent is:

1. The method of continuously treating and removing extraneous matter from well fluids in the field as they flow from the well which includes, separating the free water from the well stream, whereby the water content of the well stream is reduced, then conducting the stream into a confined body of heated water wherein said stream is heated and treated to break emulsions and to further extract water from the emulsified oil, admixing fresh water with the well stream and the body of heated water, flowing the mixture upwardly through a body of salt water, whereby extraneous matter held in suspension in the well fluids is agglomerated with the fresh water in said body of water, and precipitating the extraneous matter from the flowing fluids.

2. The method of continuously treating and removing extraneous matter from oil well fluids in the field as they flow from the oil well which includes, separating the free water from the well stream, whereby the water content of the well stream is reduced, then conducting the stream into a confined body of heated water wherein said stream is heated and treated to break emulsions and to further extract water from the emulsified oil, flowing the residue well stream upwardly through a body of heated salt water, whereby the extraneous matter held in suspension in the well stream is agglomerated with the water, and adding fresh water to the body of salt in sufficient

quantities to prevent the body from reaching a saturated condition.

3. The method of continuously treating and removing extraneous matter from well fluids in the field as they flow from the well which includes, separating the free water from the well stream, whereby the water content of the well stream is reduced, then conducting the stream into a confined body of heated water wherein said stream is heated and treated to break emulsions and to further extract water from the emulsified oil, flowing the residue well stream upwardly through a body of heated salt water, whereby the extraneous matter held in suspension in the well stream is agglomerated with the water, adding fresh water to the body of salt water in sufficient quantities to prevent the body from reaching a saturated condition, and precipitating the extraneous matter from the flowing well fluids.

4. In a desalting apparatus, the combination of an emulsion treater having means for conducting a well stream thereunto, means for first permanently separating free gas from the influent and means for washing the oil in a body of heated water in dispersed order, a conductor for discharging the washed oil from the treater, and a desalting tank having an inlet connecting with the oil discharge of the treater, means for introducing fresh water into the tank adjacent the oil inlet, means for maintaining a body of water in the tank through which the oil and fresh water flows upwardly, means for heating the water in

the desalting tank means for dispersing and baffling the upwardly flowing oil, and means for carrying off oil from the upper end of the tank.

5. An apparatus as set forth in claim 4, and a preheater connected in the oil discharge from the treater and also connected with the influent conducting means, said preheater having a well stream inlet, whereby the well stream is preheated by heat exchange with the washed oil.

6. An apparatus as set forth in claim 4 with a filter in the tank in the path of the upwardly flowing oil to break up water bearing oil globules.

7. The method of continuously treating and removing extraneous matter from well fluids in the field as they flow from the well which includes, separating the free water from the well stream, whereby the water content of the well stream is reduced, then conducting the stream into a confined body of heated water wherein said stream is heated and treated to break emulsions and to further extract water from the emulsified oil, admixing fresh water with the well stream and the body of heated water in sufficient quantities to absorb salt from the emulsion stream components, flowing the mixture upwardly through a body of salt water, whereby extraneous matter held in suspension in the well fluids is agglomerated with the fresh water in said body of water, and precipitating the extraneous matter from the flowing fluids.

JAY P. WALKER.
